6 Claims. (Cl. 37—171)

This invention relates to improvements in a subgrading machine and refers particularly to a machine for subgrading a relatively narrow strip on lateral sides of a road over which the tracks or wheel of a main subgrader or paving machine may travel.

In preparing a road site for paving, it is necessary to cut away or subgrade the site preparatory to laying the pavement thereon. In those types of road making operations wherein fixed forms upon which the subgrader and paving machine are adapted to ride are not used, the laying of the finished pavement can be accomplished with greater facility and more economically if the subgrade is cut to an accurate level and is devoid of humps and undulations. However, the subgrader, in order to accomplish this desired end, must itself travel over a relatively smooth properly cut path since the character of the subgrade reflects the character of the path over which the wheels or tracks of the subgrader travel.

The present invention relates to a machine which functions to cut paths or strips of relatively narrow width over which the wheels or tracks of the main subgrader are adapted to travel, and for convenience the machine embodying the features of the present invention will be hereinafter referred to as a "strip subgrader."

The machine comprising the present invention may comprise a portion of the main subgrader or the machine may be used as a separate unit. If employed as an integral portion of the main subgrader, two strip subgrading units may be employed which may be secured to the main subgrader and be disposed in advance of the paths of travel of the wheels or tracks of the main subgrader on each lateral side of the road site. Thus, the motive power for driving the main subgrader functions also to drive the strip subgraders and the strip subgraders cut accurately graded relatively narrow strips over which the following wheels or tracks of the main subgrader travel. Of course, if the strip subgraders are used as separate units they can be operated independently of the main subgraders and may operate as far in advance of the main subgrader as desired.

One of the important features of the strip subgrader comprising the present invention resides in the mounting of the cutter blade with respect to the machine frame wherein it may be raised and lowered conveniently and quickly by the operation of a single control.

Another feature of the invention resides in the mounting of the cutter blade of the strip subgrader which permits convenient adjustment of the blade as the blade wears.

A further important feature of the invention resides in a guide or gauge mechanism which permits an operator accurately to follow a grade line with a minimum of deviation therefrom.

Other important objects and features of the present invention will be apparent from the accompanying drawings and following detailed description.

In the drawings:

Fig. 1 is a top plan view of a strip subgrader embodying the features of the present invention.

Fig. 2 is a side elevational view of the device shown in Fig. 1.

2

Fig. 3 is a transverse sectional view taken on line 3—3 of Fig. 2.

Fig. 4 is a transverse sectional view taken on line 4—4 of Fig. 2.

Fig. 5 is a slightly enlarged detailed sectional view taken on line 5—5 of Fig. 2.

Fig. 6 is a transverse sectional view taken on line 6—6 of Fig. 5.

Fig. 7 is an enlarged detailed sectional view taken on line 7—7 of Fig. 2.

Fig. 8 is a top plan view of a main subgrader, shown diagrammatically, with which two strip subgraders, comprising the present invention, are associated.

Fig. 9 is a side elevational view of a strip subgrader which can be employed as a separate unit.

Referring in detail to the drawings and with particular reference to Fig. 8 thereof, 1 indicates generally a subgrader which comprises as a unitary portion thereof two strip subgraders 2 which embody the features of the present invention. The subgrader proper is shown diagrammatically and comprises parallel spaced beams or frame members 3 over which tracks or articulated treads 4 travel in an endless path. The beams 3 may be bridged by transverse frame members 5 which may carry suitable subgrading apparatus (not shown) and may also carry an engine or other prime mover (not shown) if the device is self-powered. Of course, if desired, the device may not be self-powered and may be pulled by a tractor or other traction member.

The device 1 shown may span the width of the proposed road and the opposite tracks 4 may move along the lateral edges of the road. The function of the subgrader 1 is to cut the earth to a predetermined level or grade so as to provide a foundation surface for the pavement material which will constitute the finished road.

To provide a finished road of predetermined constant thickness and with a surface brought to a predetermined grade, the subsurface cut by the subgrader must be cut to a desired predetermined grade and elevation. Further, in view of the fact that the cutting implements carried by the subgrader cut to a level determined by the surface over which the tracks 4 travel, it is vital that the surface of the strips or paths over which the tracks travel be cut to a predetermined grade. Hence, the provision of the strip subgraders 2 which cut the strip or path over which the tracks 4 travel.

In commencing operations, the engineer sets grade stakes two feet outside of the pavement area on each side of the road. These stakes are normally set at fifty-foot intervals, and represent the predetermined grade of the road at these points. Rods are driven into the ground at these points and a chalk line is strung upon these rods eighteen inches above the tops of the grade stakes. Also, to eliminate excessive sag in the chalk line, additional rods are driven into the ground between the original grade stakes and the operator sights down the line making corrections to obtain a smooth grade. The grade lines referred to hereinbefore are designated by the lines 5' in the drawings. Governed by these lines, both for lateral guidance and principally for elevational guidance, the machine comprising the present invention performs its function.

In order to prepare the path over which the tracks or treads 4 travel, a strip subgrader 2 is mounted at the forward end of each of the beams 3. Inasmuch as both strip subgraders 2 are the same, only one will be described in detail. At the forward end portion of each beam 3 a pair of spaced brackets or standards 6 are carried, said standards being supported by gussets 7. A tube or sleeve 8 is secured at its opposite ends to the standards 6 and a hollow shaft 9 extends therethrough and is rigidly secured therein. The protruding ends of said shaft func-

tion as journals for sleeves 10 on each side of the standards, said sleeves being rigidly secured to the ends of swingable arms 11. The arms 11 are thus disposed parallel to the beam 3 and are swingable in vertical planes on each side of the beam.

At the forward or face ends of the arms a sleeve 12 is rigidly secured to the arms 11, said sleeve spacing the arms from each other. In addition, the arms themselves terminate in sleeves 13 which are in alignment with sleeve 12. Each of the sleeves 13 is broken intermediate its length, as at 14 in Fig. 1, and a pin or shaft 14' bridges each break. A pair of depending arms 15 carry sleeves 16' at their upper ends, said sleeves being journaled upon the bridging pin 14' whereby the arms are swingably depending from arms 11.

A substantially horizontally disposed plate 16 is rigidly secured, as by welding 17, to the lower ends of arms 15. A gusset 18 is secured to the forward end of beam 3 on each side thereof and a substantially vertically disposed channel 19 is rigidly secured to each gusset and to each side of the beam 3. A plate 20 is secured to plate 16 and extends transversely across the subgrader 2. The plate 20 functions to stiffen and reinforce plate 16, and also has secured thereto resilient blocks or bumpers 21, preferably constructed of rubber, which are carried within the channel 19. The blocks 21 are preferably secured to plate 20 by bolts or the like (not shown). Thus the swingable assembly comprising arms 15 and plate 16 is resiliently cushioned by blocks 21.

The plate 16 is V-shaped at its front end and supports a backing plate which is preferably welded to said plate. A front skirt 22 is also rigidly secured to the plate 16, said skirt also being rigidly secured, preferably by welding, to the depending arms 15. The skirt 22 is V-shaped and is rigidly secured to a mold board 23 which is curved at its upper edge portion 24 and is inclined forwardly at its lower edge portion 25. A cutter 26 is bolted, by means of bolts 27 between the mold board 23 and the backing plate 21' and comprises the active cutting element of the strip subgrader. Additional bracing is furnished to the mold board assembly by spars or braces 28 and 29 (Fig. 1).

Thus, the cutting assembly of the strip subgrader is swingably mounted upon arms 15 and is resiliently cushioned by the blocks 21.

A top deck plate 30 is rigidly secured to the plate 20, preferably by welding, said deck plate also extending across the subgrader, as shown best in Fig. 3. At its front, the deck plate 30 is rigidly secured to the front skirt 22. An electric motor 31 is mounted upon the deck plate 30 and said plate is provided with suitable openings whereby V-belts 32 trained around pulleys 33 carried by motor shaft 34 may pass downwardly and wrap around pulleys 35 mounted upon shaft 36 of a vibrating device 37 which is secured to plate 16 by bolts 38.

The vibrating device 37 is shown in detail in Figs. 5 and 6 and comprises a casing 39 in which shaft 36 is journaled. A second shaft 40 is also journaled in the casing 39 and is disposed horizontally parallel to shaft 36. Gears 41 and 42 are respectively mounted upon shafts 36 and 40 and, hence, both shafts are driven together by motor 31, but in opposite directions. An eccentric weight 43 is carried by shaft 36 and a similar weight 44 is carried by shaft 40.

The weights 43 and 44 are so positioned upon shafts 36 and 40 and said shafts are so geared together that, during rotation, the weights pass both horizontal positions together on the same sides of their respective supporting shafts. However, they are both rotating in opposite angular directions when the above described position obtains. Accordingly, horizontally said weights are in phase and the weights exert concurrent thrusts in horizontal directions. However, when the weights are displaced 90° from their horizontal positions the weights are out of phase vertically and their thrusts are statically

balanced or neutralized, as shown by the dotted position of the weights in Fig. 6.

Hence, the vibrating device produces a maximum horizontal vibration and a minimum vertical vibration. Inasmuch as the vibrating device 37 is mounted upon plate 16, this horizontal vibration is imparted to the entire swingable assembly comprising arms 15, mold board 23 and cutter blade 26. Hence, a substantially horizontal chiseling action is produced by blade 26 upon the ground.

10 The vibration hereinbefore described is resiliently damped by the blocks 21 and is not transmitted to the machine proper.

It is to be understood, however, that the present invention in its broadest aspects contemplates other types of vibrating mechanisms. For instance, a simple eccentric rotating weight may be employed or a mechanism wherein an elliptical pattern of vibration and wherein the major vibration may occur along a horizontal line may be used.

20 A hand wheel 45 is secured at the upper end of a vertical shaft 46 by nut 47. Shaft 46 is journaled in a vertical housing 48 which is secured to a cross bar 49, preferably by welding 50, the cross bar being, in turn, secured to the opposite arms 11. Beneath the cross bar 49 a hub 51 is secured to shaft 46 and is locked thereon by set screw 52. The hub 51 carries two sprocket pinions 53 and 54. Bearing blocks 55 and 56 are carried between the flanges of opposite arms 11, being secured in place by screws 57. A self-aligning bearing 58 is carried by bearing block 55, and a similar bearing 59 is positioned in bearing block 56. A screw shaft 60 is secured to the inner race of bearing 58 by nut 61 and, in similar fashion, shaft 62 is secured to the inner race of bearing 59 by nut 63.

30 The shanks of both screws 60 and 62 carry threads 64 and 65, respectively, and a sprocket wheel 66 is threadedly mounted upon screw 60, said wheel being fastened by set screw 67. In similar fashion a sprocket wheel 68 is threadedly mounted upon screw shaft 62, being held in desired position thereon by set screw 69. A sprocket chain 70 operatively connects sprocket pinion 53 and sprocket wheel 66, and chain 71 similarly connects pinion 54 and wheel 68.

A tie plate 72 extends across the device and is secured 45 to the beam 3 and the upper ends of the channel 19, preferably by welding. A nut 73 is carried by the underside of the tie plate 72 adjacent screw shaft 60 and a similar nut 74 is similarly secured to the tie plate adjacent screw shaft 62. The screws 60 and 62 are respectively threaded in the nuts 73 and 74.

The arrangement is such that when hand wheel 45 is rotated, screw shafts 60 and 62 are rotated and, hence, arms 11 are moved upwardly or downwardly relative to beam 3. Inasmuch as the suspended assembly comprising arms 15, plate 16, mold board 23, etc. are suspended from arms 11, movement of screw shafts 60 and 62 raises or lowers the cutting mechanism relative to beam 3. In view of the fact that movement of arms 11 is along an arc, screw shafts 60 and 62 will have a slight 55 degree of angularity in their movement. This contingency is compensated for by the self-aligning bearings 58 and 59.

It will be noted that the sprocket wheels 66 and 68 may be rotated freely about the respective screw shafts 60 and 62 by loosening the respective set screws 67 and 69. By this arrangement an adjustment for uneven wear of blade 26 may be brought about. For instance, were blade 26 to wear to a greater degree on one side or the other, one or the other of the set screws 67 or 69 70 may be loosened and hand wheel 45 may be turned. This causes the loosened sprocket wheel to rotate to a degree upon its shaft. Thereafter the sprocket wheel may be locked by its set screw. This operation tends to warp the portion of the machine comprising arms 11, arms 15, plate 16, etc., and thereby transversely cant

the cutter blade 26. The frame, although essentially rigid, will permit a moderate degree of warp sufficient to adjust normal uneven wear of the blade 26.

To further provide for wear of the blade 26, the holes therethrough for the reception of bolts 27 are centrally disposed transversely of the blade and, hence, said blade may be reversed edge-for-edge when the active edge wears to an excessive degree.

To inform the operator of the necessity of manipulating the hand wheel 45 to raise or lower the blade 26 and its supporting structure relative to beam 3, a system of levers 75 are employed. The system of levers 75 comprises a lever 76 which is pivotally mounted upon shaft 14'. The lever 76 is pivoted intermediate its length but the pivot point is closer to the rear end of the lever than to its front end. The lever 76, at its rear end is pivotally connected to a link 77 by pivot pin 78 and the latter link is pivotally connected at its opposite end to a second link 79, the pivot comprising pin 80. Link 79 is fulcrumed upon pin 81 which is carried by tube 82 secured to beam 3, the tube being also secured to channel 19. The fulcrum 81 is positioned adjacent the rear end of link 79 whereby the lever arm of the forward portion of said link is relatively greater than the rear lever arm. At the rear end of link 79, said link is pivotally connected to clevis 83 by pin 84. A similar clevis 85 is pivotally mounted upon arm 11 by pivot pin 86. A screw 87 is threadedly connected at its opposite ends to clevises 83 and 85, the threads at the opposite ends of the screw being pitched in opposite directions. A nut 88 is carried intermediate the length of screw 87 whereby said screw may be conveniently rotated to change the effective distance between pins 84 and 86. Hence, by manipulating nut 88 the forward end of lever 76 may be raised or lowered, a slight motion of screw 87 resulting in a large motion of the free end of lever 76.

At the forward or free end of lever 76 a pair of spaced ears 89 are carried and a sleeve 90 is positioned therebetween. A pin 91 is carried in sleeve 90 whereby said sleeve may rotate about said pin. A tube 92 is fixed to the sleeve and carries at one end a pointer 93. A coil spring 94 is anchored at one end upon lever 76 and at its opposite end upon tube 92. It will be noted that sleeve 90 is offset outwardly from the face of lever 76 and, hence, under the tension of spring 94, the tube 92 laterally abuts the end of said lever. In this position, the tube and pointer 93 extend at substantially right-angles to the outer face of lever 76. It will also be noted that the tube 92 and pointer 93 are free to rotate in the opposite direction against the tension of spring 94 to a position substantially parallel to the face of the lever 76.

A pin 95 is slidably positioned in the hollow shaft 9. The pin 95 is normally in retracted position wherein flange 96 carried by said pin abuts the end of the shaft. However, when occasion demands the pin may be moved to extended position, as shown best in Fig. 1.

It will be noted that the point of pin 95 is at a fixed elevation above the lower face of the treads 4, that is, the level of the surface cut by the strip subgrader. It is desired that the point of pin 95 be at the same elevation as the grade line 5' and that the strip subgrader cut sufficient of the earth to normally have this condition obtain. Hence, by the manipulation of nut 88 the point of pointer 93 is so set as to be the same distance above the cutter's edge 26 as the pin 95 is above the treads 4. Hence, thereafter by so manipulating hand wheel 45 so as to raise or lower arms 11 to maintain the pointer 93 coincident with the grade line 5', the desired depth of cut may be obtained.

As has been hereinbefore described, a relatively small movement of screw 87 results in a relatively large movement of pointer 93. Conversely a relatively large move-

ment of pointer 93 represents a relatively small movement of arms 11 and, hence, cutter blade 26. Accordingly, a relatively small movement of hand wheel 45 represents a relatively large movement of pointer 93.

The particular purpose of the pointer 93 and its motion multiplying linkage is to mitigate duplication in the strip being graded of the deviations from intended grade elevation of the grade line or chalk string 5', especially the deviations resulting from sagging of the string or line between grade stakes and inaccurate sight placement of line supporting rods intermediate the grade stakes. In use of the device, initial portions of the strips to be graded are leveled off to the intended grade, and the strip subgrader is moved onto these leveled areas with its pointers 93 and 95 level with the chalk line. The strip subgrader is then moved forwardly and as it is moved an operator at each hand wheel 45, by appropriate manipulation of the wheel, causes the respective pointer 93 to be maintained level with the respective string line 5'. As will be appreciated from the foregoing, relatively great movement of the pointer 93 by the hand wheel will result in only a relatively slight movement of the cutter blade 26. Thus, deviations of the string from intended elevation, as by sagging, will be reduced in transmitting this deviation from the pointer to the cutter blade. For example, with a thirteen-to-one linkage arrangement, a one inch sag in the string line will, with appropriate manipulation of the hand wheel 45, result in only one thirteenth of an inch deviation in the graded strip, which is of great importance in the formation of a road surface complying with modern specifications.

By virtue of the above described action, the cutting blades 26 cut extremely accurate foundation surfaces over which the tracks 4 subsequently ride, whereby the device under normal conditions will continue to cut extremely accurate foundation strips. The pointer and its multiplying linkage, of course, will not operate properly in reverse. If for some reason the track 4 or the blade 26 were caused to deviate, which would be most unusual when considering customary working conditions and the normal operation of the blades and tracks, any deviation of the track would be directly reflected by an equal deviation of the pointer 93, and adjustment of the hand wheel 45 to bring the pointer back to the grade line would bring the blade 26 only partially back to intended position, thereby resulting in error in the grading operation. However, any such error would be revealed to the operator the next time the pointer 95 passed a grade stake, since this pointer should be level with the string at each and every grade stake, so that the error would be revealed and could be corrected within no more than 50 feet of travel of the strip subgrader.

Hence, during the operation of the device, the operator attempts to maintain the pointer 93 opposite the grade line 5'. The human element, however, prevents an exact alignment, but if an approximate alignment is maintained errors in the raising and lowering of the cutter blade 26 will be extremely small. Accordingly, abrupt and large changes of elevation of the strip being cut will be avoided since all the operator need do is maintain an approximate alignment of pin 93 with grade line 5', and check the pin 95 relative to the line at each grade stake.

In the form of the invention illustrated in Figs. 1 to 8 inclusive, the strip subgrader is shown as being an integral portion of the main subgrader. Accordingly, only the front terminal sprockets 97 for the treads or track 4 are carried by the strip subgrader. In Fig. 9 a unit strip subgrader 98 is illustrated. In this form of the invention, all of the mechanism hereinbefore described is identical and corresponding reference numerals will be applied without further detailed description. However, being a separate unit, both terminal sprockets

99 and 100 for the tracks are carried by the unit strip subgrader itself.

The unit strip subgrader 98 may be used as a separate unit or units in front of the main subgrader or the unit strip subgrader may be employed to prepare a properly graded path for a so-called slip form paver or the unit may be separately employed to prepare a properly graded strip for any desired purpose.

We claim as our invention:

1. A strip subgrader which comprises in combination, a frame having a front and rear portion, a pair of spaced arms pivotally mounted at corresponding ends upon said frame and having their opposite ends extending toward the front portion of said frame, a support pivotally carried at said opposite end portions of said arms and depending substantially vertically therefrom, a cutter blade carried by said support, and control means carried by said arms and bearing on said frame for vertically moving said arms relative to said frame to raise and lower said cutter blade relative to said frame, said control means comprising screw means journaled in said arms and threadedly engaging said frame, shaft means carried by said arms for manipulating said screw means to change the position of said arms relative to the frame, said shaft means comprising a rotatable shaft, sprocket wheels carried by said shaft, sprocket wheels threadedly carried by said screw means, sprocket chains respectively engaging said shaft sprocket wheels and said screw sprocket wheels, and separate means for locking each of said screw sprocket wheels upon said screw means.

2. A strip subgrader which comprises in combination, a frame having a front and rear portion, spaced arms pivotally mounted at corresponding ends upon said frame and having their opposite ends extending toward the front portion of said frame, a support pivotally carried at said opposite end portions of said arms and depending substantially vertically therefrom, a cutter blade carried by said support, and control means carried by said arms and connected to said frame for vertically moving said arms relative to said frame to raise and lower said cutter blade relative to said frame, said control means comprising spaced vertical screws threadedly engaged with said frame, each of said arms bearing upon one of said screws and being movable with axial movement of said screws, and means carried by said arms for simultaneously rotating said screws.

3. A strip subgrader which comprises in combination, a frame having a front and rear portion, spaced arms pivotally mounted at corresponding ends upon said frame and having their opposite ends extending toward the front portion of said frame, a support pivotally carried at said opposite end portions of said arms and depending substantially vertically therefrom, a cutter blade carried by said support, control means carried by said arms and connected to said frame for vertically moving said arms relative to said frame to raise and lower said cutter blade relative to said frame, and vibratory means carried by said support for vibrating said support and cutter blade carried thereby, said control means comprising spaced vertical screws threadedly engaged with said frame, each of said arms bearing upon one of said screws and being movable with axial movement of said screws, means carried by said arms for simultaneously rotating said screws, said means comprising a shaft rotatably carried by said arms, means connecting said shaft to each of said screws to rotate said screws simultaneously to axially move said screws.

4. A strip subgrader which comprises in combination, a frame having a front and rear portion, spaced arms pivotally mounted at corresponding ends upon said frame and having their opposite ends extending toward the front portion of said frame, a support pivotally carried at said opposite end portions of said arms and depending substantially vertically therefrom, a substantially horizontally disposed platform carried by said support, a cutter

blade carried by said platform, vertical screw means threadedly engaged with said frame and rotatably but nonaxially movable with respect to said arms for vertically moving said arms relative to said frame to raise and lower said platform and cutter blade carried thereby relative to said frame, a shaft rotatably carried by said arms, separate means connecting said shaft to each of said vertical screw means to simultaneously rotate said screw means, and means carried by said separate means for rendering selectively a separate means inoperative, and vibrating means carried by said platform to vibrate said platform and cutter blade carried thereby.

5. A strip subgrader which comprises in combination, a frame having a front and rear portion, spaced arms pivotally mounted at corresponding ends upon said frame and having their opposite ends extending toward the front portion of said frame, a support pivotally carried at said opposite end portions of said arms and depending substantially vertically therefrom, a cutter blade carried by said support, control means carried by said arms and bearing on said frame for vertically swinging said arms relative to said frame to raise and lower said cutter blade relative to said frame, a multiplying linkage pivotally connecting one of the arms and said frame, an index carried by said linkage for alignment with a grade line, said index being simultaneously movable with said arm in the same direction but at a multiplied rate.

6. A strip subgrader which comprises in combination, a frame having a front and rear portion, spaced arms pivotally mounted at corresponding ends upon said frame and having their opposite ends extending toward the front portion of said frame, a support pivotally carried at said opposite end portions of said arms and depending substantially vertically therefrom, a cutter blade carried by said support, control means carried by said arms and bearing on said frame for vertically moving said arms together relative to said frame to raise and lower said cutter blade relative to said frame, a multiplying linkage pivotally connecting said arms and said frame, an index carried by said linkage for alignment with a grade line, said index being movably responsive in a multiplied degree to the movement of said arms, said multiplying linkage comprising a plurality of pivotally connected links, means connecting one link to said frame, a second link pivotally connecting said frame-connected link to said arm, a third link pivotally connected to the forward end portion of said arm and having a free end, a fourth link pivotally connecting said frame-connected link to said third link, said index being carried by the free end of said third link and movable in response to movement of said control means, one of said links being adjustable in length to calibrate said index with respect to the position of the arms relative to the frame.
